PRIMER MANUFACTURE

Clarence Walton Musser, Philadelphia, Pa.

Application June 16, 1942, Serial No. 447,301

5 Claims. (Cl. 113—42)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a method of producing a mechanical draw piece, more particularly a primer cup as an ammunition component, with the head flattened during its fabrication.

Draw pieces with a flattened head portion are generally produced by drawing the metal against a spring, hydraulic or pneumatic pressure plate or punch which ejects the finished drawn piece by returning it through the die. In the manufacture of a flat headed primer cup as a component for ammunition, a separate machine and operation are used to secure the desired flattening of the head. This latter method requires an additional handling and an extra operation. Returning the draw piece through the die has definite speed limitations and imparts a greater degree of wear to the die with consequent greater tool maintenance.

The object of the invention is to provide a rapid, single operation method of producing flat headed draw pieces, more particularly primer cups, by the addition of a device easily manufactured and attached to existing draw press equipment; which will not increase the normal die wear and maintenance; which is easily adjusted for variation in thickness and stiffness of stock; and which will produce a more normally uniform draw piece.

Due to the variation and extent of present draw press equipment, the inventive idea involved is capable of receiving a wide variety of mechanical applications or embodiments. For illustrating one possible embodiment this invention is shown in the accompanying drawings wherein:

Fig. 1 is a double acting press with the head flattening device attached.

Fig. 2 is an enlarged view in section substantially on line 2—2 of Fig. 1.

Fig. 3 is a detail of a cup and dies, in which the head curvature has been modified by flat-faced dies in a separate operation.

Fig. 4 is a detail of a cup and dies, in which the cup head has been flattened in the draw press by dies having curved surfaces.

Fig. 5 is a section through the dies showing the cup near the end of the drawing stroke.

Fig. 6 is a similar view showing the cup contacting the backing member for flattening.

Fig. 7 is a similar view showing the draw punch being withdrawn from the cup, and

Fig. 8 is a similar view showing the finished cup being ejected.

To produce flat headed draw pieces by this invention, the piece is cupped and drawn through dies in a conventional manner, and then near the bottom of the draw stroke, brought into contact with a backing punch which flattens the head of the draw piece against the end of the draw punch during the final movement of the draw stroke. The completed flattened draw piece is stripped off the draw punch on its return stroke by the bottom of the die and is ejected by an air blast.

Figs. 1 and 2 show a double acting press which performs the blanking and drawing operations in one revolution of the crankshaft 1. The blanking and cupping die 2 and the sizing (redrawing) die 3 are held rigidly in the die holder 6 by the die holder plate 7 and cap screws 8. The die holder 6 is fastened to the press 4 by cap screws 5. Cap screws 5 permit alignment of the blanking and cupping die 2 with the blanking punch 9 and the cupping and drawing punch 10. The blanking punch 9 is fastened, through punch holder block 11, to the moving ram 12 and actuated in a vertical plane by the connecting rods 13 journaled to the crank pins 14 of crankshaft 1. The blanking punch 9 also acts as a bushing which centers the lower end of the drawing punch 10 in reference to the blanking edge of the blanking punch 9. The draw punch 10 is fastened to the internal ram 15 and is actuated in a vertical plane by the connecting link 16 journaled to the crank pin 17 of the crankshaft 1. The crank pins 14 and 17 are so spaced, angularly about the shaft's axis, that the blanking stroke is completed before 35 the drawing operation is started.

The sizing die support 18 has an air duct 19 connected to an air line 20. This air line 20 is connected to a compressed air supply and is controlled by a regulating valve.

In the mechanism which actually does the flattening of the head of the draw piece, a punch guide 21 is fastened by cap screws 22 to the press stand 23. The axis of the backing punch 24 coincides with the axis of the draw punch 10 and is permitted a small vertical movement by the arcuate plate spring 25 which has hardened steel bearing plates 26 on each side to protect the adjusting screw 27 and the end of the backing punch 24. The adjusting screw 27 is retained in adjustment by the locknut 28.

The lower end of the draw punch 10 is concave and the top end of the backing punch 24 is convex as shown in Fig. 4. This, acting on the usual and natural degree of convexity for the draw piece being fabricated, will produce a flat head

on the draw piece 30 through the elastic recovery of the metal in the head counteracting the deflection it has received in excess of a flat head. When a draw piece is flattened against a flat platen or punch, the elasticity of the metal in the draw piece returns it partially to its original curved contour. This is shown in draw piece 31, Fig. 3, where a punch 32 enters the cup and presses it against the platen 33. Furthermore, in the case of a separate operation, the side walls frequently fail of perpendicularity with the bottom of the head, as the punch 32 does not become accurately aligned with the draw piece 31 upon entering it.

What is the proper curvature for backing punch 24 depends upon the characteristics of the piece being formed, such as material, thickness, diameter, etc. and must be determined in each case.

In order to collect the finished draw pieces, a chute 34 is placed around the punch guide 21, encompassing the hole 4' through the press bed from which the draw piece is ejected. The finished flattened draw piece is carried through this chute 34 to a tray 29.

Actual operations on the work piece at the end of the draw stroke are more clearly illustrated in Figs. 5 to 8. In Fig. 5 the primer cup 30 is shown near the end of the draw stroke, but not yet in contact with the backing punch 24. In Fig. 6 it has been carried completely beyond the draw die and flattened by contact with the backing punch. This will have a tendency to spread the side walls so that on the return stroke of the draw punch 10, if the cup does not fall therefrom by itself, it will be stripped on contacting the bottom of the draw die. In Fig. 8 the primer cup is shown being ejected by the blast of air indicated by the arrows.

In operation, the stock from which the draw piece 30 is made is fed through channel 35 in die holder plate 7. This channel 35 centers the stock directly beneath the blanking punch 9 and the draw punch 10. As the crankshaft rotates, crank pins 14, through connecting links 13, cause ram 12 to descend. This movement carries the blanking punch 9 into contact with the stock and then with the further completing movement of the crank stroke, stamps out a disk from the stock. With further rotation of the crankshaft, the blanking punch 9 ascends and the draw punch 10 descends to contact the sheared out blank and carries it through the draw die 2 and the sizing die 3.

Near the end of the working stroke of the press, the draw piece 30, now completely through the dies 2 and 3 and frictionally held on the draw punch 10, is forced against the backing punch 24. On completion of the draw stroke, sufficient pressure is built up, through loading of spring 25, to flatten the draw piece between draw punch 10 and the backing punch 24. To secure this required degree of pressure at the lowest portion of the draw stroke, adjustment screw 27 is adjusted and locked in position with the locknut 28.

As draw punch 10 ascends with continued rotation of shaft 1, the bottom of sizing die 3 strips draw piece 30 from the draw punch. Draw piece 30 is then blown by an air blast from the air duct 19, through hole 4' in the press bed and into the chute 28.

Although compressed air has been indicated herein as a means of removing one draw piece before another draw piece is to be flattened.

there are many different mechanical or electrical devices which could be used to secure this result. A movable, pivoted or sliding, lever, or other mechanical device could be synchronized with the press stroke to sweep or deflect the stripped draw piece 30 into the chute 34 without departing from the basic invention. Other modifications will be evident to those skilled in the art.

I claim:

- 10 1. In a machine for forming a flat-headed cup-shaped member out of sheet stock, the combination of a die having input and discharge ends, a draw punch having a working face and being axially movable from a starting position where
15 said face is spaced from said die's input end toward and through said die to a finishing position where said face is more than said cup member's length beyond said die's discharge end, means for severing a blank from said stock and
20 for placing said blank between said draw punch face in its said starting position and the input end of said die, means thereafter effective for moving said draw punch from its said starting position toward its said finishing position whereby to force said blank through said die and thereby form it into a cup-shaped member having a rounded head, and a backing punch with a working face placed more than said cup member's length beyond said die's discharge end and there
25 so restrained that upon advancement of said draw punch to its said finishing position said face of the backing punch contacts the round head of said cup-shaped member and flattens it against the working face of said draw punch,
30 35 so that the said working faces of said draw and backing punches being so oppositely curved that there is set up during said flattening operation a reverse bending in said cup member head which overcomes the elastic recovery tending to round
40 the head.
2. In a machine for forming a flat-headed cup-shaped member out of sheet stock, the combination of a die having input and discharge ends, a draw punch having a concavely shaped face and
45 being axially movable from a starting position where said face is spaced from said die's input end toward and through said die to a finishing position where said face is more than said cup member's length beyond said die's discharge end, means for severing a blank from said stock and
50 for placing said blank between said draw punch face in its said starting position and the input end of said die, means thereafter effective for moving said draw punch from its said starting position toward its said finishing position whereby to force said blank through said die and thereby form it into a cup-shaped member having a rounded head, and a backing punch with a convexly shaped face placed more than said cup member's length
55 beyond said die's discharge end and there so restrained that upon advancement of said draw punch to its said finishing position said convex face of the backing punch contacts the round head of said cup-shaped member and flattens it against the said concave face of said draw punch by a reverse bending which overcomes the elastic recovery tending to round the head.
3. In a machine for forming a flat-headed cup-shaped member out of sheet stock, the combination of a die having input and discharge ends, a draw punch having a concavely shaped face and
70 being axially movable through said die between a starting position spaced from said die's input end and a finishing position spaced more than said cup member's length from said die's output end.

means for severing a blank from said stock and for placing said blank between said draw punch in its said starting position and the input end of said die, means thereafter effective for moving said draw punch toward its said finishing position whereby to force said blank through said die and thereby form it into a cup-shaped member having a rounded head, a backing punch with a convexly shaped face placed more than said cup member's length beyond said die's discharge end and there so restrained that upon advancement of said draw punch to its said finishing position said convex face of the backing punch contacts the round head of the cup-shaped member and flattens it against the said concave face of said draw punch by a reverse bending which overcomes the elastic recovery tending to round the head.

4. In a machine for forming a flat-headed cup-shaped member out of sheet stock, the combination of a die having input and discharge ends, a draw punch having a working face and being axially movable from a starting position where said face is spaced from said die's input end toward and through said die to a finishing position where said face is beyond said die's discharge end, means for severing a blank from said stock and for placing said blank between said draw punch face in its said starting position and the input end of said die, means thereafter effective for moving said draw punch from its said starting position toward its said finishing position whereby to force said blank through said die and thereby form it

5 into a cup-shaped member having a rounded head, and a backing punch with a working force placed beyond said die's discharge end and there so restrained that upon advancement of said draw punch to its said finishing position said face of the backing punch contacts the round head of said cup-shaped member and flattens it against the working face of said draw punch, the said working faces of said draw and backing punches being so oppositely curved that there is set up during said flattening operation a reverse bending which overcomes the elastic recovery tending to round the head.

10 5. In a machine for forming a flat-headed cup-shaped member out of sheet stock, the combination of a die having input and discharge ends, a draw punch having a concavely shaped face and being axially movable from a starting position where said face is spaced from said die's input end toward and through said die to a finishing position where said face is beyond said die's discharge end, means for severing a blank from said stock and for placing said blank between said draw punch face in its said starting position and the input end of said die, means thereafter effective for moving said draw punch back through said die to its said starting position, means including said die's discharge end then operative to strip said cup-shaped member from said draw punch and thus completely free it on the discharge side of the die, and ejecting means effective to move the thus freed cup from between said die and said backing punch and thence out of said machine.

15 20 25 30 35 40

6. In a machine for forming a flat-headed cup-shaped member out of sheet stock, the combination of a die having input and discharge ends, a draw punch having a working face and being axially movable from a starting position where said face is spaced from said die's input end toward and through said die to a finishing position where said face is beyond said die's discharge end, means for severing a blank from said stock and for placing said blank between said draw punch face in its said starting position and the input end of said die, means thereafter effective for moving said draw punch from its said starting position toward its said finishing position whereby to force said blank through said die and thereby form it having a rounded head, and a backing punch with a convexly shaped face placed beyond said die's discharge end and there so restrained that upon advancement of said draw punch to its said finishing position said convex face of the backing punch contacts the round head of said cup-shaped member and flattens it against the said concave face of said draw punch by a reverse bending which overcomes the elastic recovery tending to round the head.

C. WALTON MUSSER.
